COLLAPSIBLE GRILLAGE GUARD FOR DOOR AND WINDOW OPENINGS

Filed March 13, 1931

UNITED STATES PATENT OFFICE

1,920,416

COLLAPSIBLE GRILLAGE GUARD FOR
DOOR AND WINDOW OPENINGS

Ernst Melaun, Indianapolis, Ind.

Application March 13, 1931. Serial No. 522,219

2 Claims. (Cl. 20—71)

This invention relates to a collapsible grillage guard for openings such as windows, doors and the like.

The chief object of this invention is to provide a collapsible construction of the aforesaid character which will be quite ornamental and which furthermore will be of the link mesh type and readily extensible and collapsible and when extended will have substantially the same strength as the more rigid lazy tongs guard constructions heretofore employed, and when collapsed, may be positioned in a space approximately one twenty-second of the space originally occupied when extended, so that the collapsed grillage may be compactly positioned immediately adjacent the side of the opening in a relatively unobtrusive, obscure manner.

The chief feature of the invention consists in the construction of a grillage of the aforesaid character, whereby the aforesaid object is accomplished.

Other objects and features will be set forth more specifically hereinafter.

The full nature of the invention will be understood from the accompanying drawing and the following description and claims:—

In the drawing, Fig. 1 is an elevational view of a portion of an opening with the collapsible grillage associated therewith in the extended position.

Fig. 2 is a vertical, sectional view taken on line 2—2 of Fig. 1 and in the direction of the arrows.

Fig. 3 is an elevational view of one portion of the grillage in the collapsed position.

Fig. 4 is an enlarged, elevational view of a plurality of links forming the grillage and the connecting member therebetween.

Fig. 5 is a side view of one of the links.

Fig. 6 is an enlarged, longitudinal, sectional view through the interlocking connection between two interlocking parts forming one of the support and retaining members.

Fig. 7 is an elevational view of the upper portion of a doorway provided with one form of the invention.

Fig. 8 is a transverse, sectional view showing the grillage of Fig. 7 in the collapsed position.

Fig. 9 is a top plan view of one of the simplest forms of the invention.

Fig. 10 is a transverse, sectional view through a modified form of grillage mounting, showing the same associated with a door opening, and the same may be the lower support and retaining structure associated with the embodiment of the invention shown in Figs. 7 and 8.

Fig. 11 is a top plan view of a portion of the threshold shown in Fig. 10.

In the drawing 10 indicates the top of the window opening, 11 the bottom thereof and 12 a side thereof. Mounted along the side wall is a side bar 13 and the same is suitably apertured as at 14 for anchoring the grillage. A center bar 15 is similarly apertured as at 16 and the center bar is movable toward the side bar in the collapsing of the grillage. The grillage includes a plurality of rectangularly arranged links 17 having the eyes 18, the eyes of adjacent links being connected together by the ring 19.

There is thus formed a type of grillage of links and rings which has all of the strength of a lazy tongs guard but which is flexible and which may be collapsed into substantially the same overall length as the grillage occupies when extended, thereby differentiating from the lazy tongs arrangement which upon collapse elongates.

A pair of tubes herein shown square and indicated by the numerals 20 and 21—see Fig. 6—is interlocking associated as at the parting 22 and by a plunger 23 which is slidably supported in one tube and in the projected position is telescopically receivable by the open end of the adjacent tube. A longitudinal slot 24 in the end of the plunger supporting tube receives a pin 25, which is secured to the plunger 23 so that the plunger may be readily moved from the retracted and dotted line position—see Fig. 6—to the projected and interlocking position, as shown by the full lines therein. When thus associated together, the tubes 21 and 22 form a complete support across the opening defined by the walls 10 and 11 and the side walls 12.

An anchorage 26 is slidably supported on said tube construction and is connected to the adjacent ring 19. The other end of the tube 21 is pivotally connected as at 27 to an associated part 28 which in the present form is shown rigidly mounted.

The lower support and retaining member construction is of a character similar to that shown in Fig. 6, but in this instance, folds upwardly and as shown clearly by comparison between the upper and lower portions of Fig. 1, the lower member 28 is shorter than the upper member 26 and the lower tube 21 is longer than the upper tube 20, so that when the tubes 21 are released from interlocking engagement with the adjacent tubes 20 in alignment therewith, the lower tube 21 may be folded upwardly and the upper tube 20 may be folded downwardly, the latter retaining the upwardly folded tube in the collapsed position, see 110

Fig. 3. Prior to the separation of the interlocking tubular portions and the folding of the same, the two center bars 15 are disconnected, since each mounts a catch pin 30 and each pivotally mounts 5 at 31 a hook 32.

Each of the center bars 15 also supports the eyeleted brackets 33 and said brackets, when the two center bars are positioned side by side, may be locked together by any suitable lock, thereby 10 locking the entire grillage in the extended and guarding position.

When the grillage is to be collapsed, the lock is opened, removed from the eyeleted brackets, the two hooks are elevated from the locking pins or 15 catches and the two center bars are slid along the supporting and retaining members 20 and 21 toward their respective side bars 13. In this sliding movement, each of the anchorages 26 is progressively picked up and caused to move to- 20 ward the portions 28 and the side bar 13. When all of the anchorages 26 have been mounted upon the portions 28 and the center bar 15 is similarly positioned upon the supports 28, the lower tubes 20 and 21 are folded upwardly and the upper tubes 20 and 21 are folded downwardly, thereby 25 retaining the entire construction through the weight of upper tubes 20 and 21 in the collapsed position.

In Fig. 9 there is illustrated a modified form of the invention. In this form of the invention, 30 there is provided a window opening 110 in the wall 111 that joins a side wall 112. A pair of L-shaped support members 121 having the angular end 128 rigid therewith is permanently mounted 35 at each end as at 100. Slidably mounted upon the upper and lower L-shaped support and retaining members, only the upper member being illustrated herein, is the grillage and the same includes the usual anchorages 126. The purpose 40 of the angularly extending portion 128 is to permit the grillage to be collapsed and positioned at one side of the window opening and to be positioned in the corner so that it will not be in the way.

45 In Figs. 7 and 8, there is illustrated a modified form of the invention, wherein 210 indicates a door frame and mounted upon the side portion 212 there is a hinged construction 200 which supports an inverted L-shaped member or a U-shaped member having the vertical portion 213 and the angular extensions 228. The grillage is suitably secured at one side to portion 213 and the anchorages 226 are slidably supported by the portion 228 and a cable 221 is suitably secured 50 at one end to the free end of the angular portion 228. Adjacent the other end of the cable is mounted a vertical bar 215, which is slidably mounted upon the cable and through the upper end of said bar projects the headed anchor member 232 carried by the end of the cable and which is receivable by a slot 230 formed in the bracket 55 231.

The vertical member 215 carries the hasp 233 and associated therewith is a staple 234 and a 60 lock 235 for locking the grillage in the extended and guarding position. When the opening is not to be guarded, the hasp is removed from the

staple, the linkage is collapsed until the bar 215 has been moved so it is supported by the angular portion 228, and then the catch and latch arrangement at the upper right hand corner is disassociated. Thereafter, the entire construction 80 may be swung upon the hinge arrangement 200, as shown in Fig. 8 and positioned to one side of the opening.

If another cable 221 is not to be employed at the bottom of the construction, the modification shown in Figs. 10 and 11 may be employed. In this formation, the threshold 311 includes an elongated slot 320 which is enlarged as at 321 and the rings 319 are connected to a double link arrangement 326 which constitutes the anchorage, one link being positioned transversely of and laterally movable in the opening 321 and the other link being longitudinally positioned therein as shown. 90

In this form of the invention, the member 215 would terminate in an inverted T-shaped head, 95 the head portion being receivable by the portion 321 of the slot and the neck being receivable by the restricted or mouth portion 320 of the slot. The door 300 is shown positioned offset with respect to the threshold and the grillage, so that 100 the grillage may be positioned adjacent the door and not prevent closing of the door.

In Fig. 11 there is illustrated a lateral enlargement 301 in the mouth 320 through which the transversely movable links are inserted and the 105 head portion of the member 215 may be inserted if the same be employed.

The invention claimed is:—

1. A collapsible grillage guard for openings such as windows and doors, including a pair of 110 substantially parallel support and retaining members positioned in juxtaposition to opposite sides of the opening to be guarded, a plurality of substantially parallel anchorages slidably associated with said members and approximately 115 transverse thereto, a plurality of rings adapted to lie in a single plane including the anchorages and the support members, and a plurality of links also in said plane, each having eyes at opposite ends, one eye being loosely connected to a ring or an- 120 anchorage and extending diagonally and the other eye of said link being loosely connected to another ring for forming a collapsible rectangularly ar- 125 ranged link grillage whereby the grillage may be collapsed into a small compass and when col- lapsed does not extend longitudinally beyond the spacing between the parallel supports and lies between the anchorages and does not project laterally from said plane.

2. A device as defined by claim 1, characterized 130 by each support being formed of a separate short portion at one end and the remaining portion of each support being movable out of the way, said anchorages being operatively associated with said short portions, one of said anchorages being rigid 135 therewith and the other in the collapsing of the grillage being slidable thereon, the remaining portions of said supports being collapsible to- 140wards each other for retaining the grillage and slidably supported anchorage in collapsed relation.

ERNST MELAUN.
